FIG. 1.

FIG. 2.

FIG. 3.

FIG. 4.

Inventor:

Isidor N. Pollingher,
by his attorney,
Charles D. Gooding.

UNITED STATES PATENT OFFICE.

ISIDOR N. POLLINGHER, OF BROCKTON, MASSACHUSETTS.

HOSE SUPPORTER.

1,407,082.

Specification of Letters Patent.

Patented Feb. 21, 1922.

Application filed September 23, 1920. Serial No. 412,196.

To all whom it may concern:

Be it known that I, ISIDOR N. POLLINGHER, a citizen of the United States, residing at Brockton, in the county of Plymouth and State of Massachusetts, have invented new and useful Improvements in Hose Supporters, of which the following is a specification.

This invention relates to an improvement in hose supporters.

The object of the invention is to so construct a hose supporter that said supporter may be secured around the leg in such a manner that the leg will be protected against contact with the metal parts of the fastening device which is so concealed as to also be prevented from catching in the clothing.

The invention consists in the combination and arrangement of parts set forth in the following specification and particularly pointed out in the claims thereof.

Referring to the drawings:

Figure 1 represents a front elevation of a hose supporter embodying my invention.

Fig. 2 is a front elevation of a portion of the hose supporter, the same also being partly broken away to more clearly illustrate the device.

Fig. 3 is a vertical section taken on the line 3—3 of Fig. 1.

Fig. 4 is a horizontal section taken on the line 4—4 of Fig. 1.

Like numerals refer to like parts throughout the several views of the drawings.

In the drawings, 1 represents a member constructed of elastic material adapted to extend around the leg, and having a buckle 2 of any desired type by which the length of said elastic member may be varied. Attached adjacent to an end 3 of the elastic member 1 is a member 4 constructed of flexible material as, for example, leather. The member 4 is formed of one piece of material and extends transversely around the elastic member 1, being attached thereto by a plurality of rows of stitches 5. The rows of stitches 5 are located adjacent to an edge 6 of the flexible member 4 and extend transversely across the elastic member 1 to a point just below the lower edge thereof and thence transversely across the flexible member 4 parallel with said lower edge thereby forming a pocket 7 in which the end 3 of the elastic member 1 is located. The width of that portion of the flexible member 4 which is adjacent to the elastic member 1

and which forms the pocket 7 is increased in order to increase the area of said pocket.

The rear portion of the flexible member 4 extends downwardly at 8 from the elastic member 1 to a point 9 and thence upwardly at 10, thereby forming a loop 11 at the lower end of which is secured the base portion 12 of a button 13, the said button forming a portion of a clasp 14. The front portion of the flexible member 4 is turned under just below the horizontal stitching 5 to form a loop 15 to receive a member 16 also forming a portion of the clasp 14. The opposite extremities of the flexible member 4 are secured simultaneously between the front and rear portions of said flexible member by means of the stitches 5.

Enclosing the end 3 of the elastic member 1 is a tip 17 constructed of suitable sheet material. The tip 17 is secured between the flexible member 4 and the elastic material 1 by the stitches 5 simultaneously with the operation of securing the flexible member 4 to the end of said elastic material. An eyelet 18 is located adjacent to the end 3 of the elastic member 1, being inserted through both layers of the tip 17 and the elastic material therebetween, being clinched over the rear side of said tip. The eyelet 18 is adapted to receive a hook portion 19 of a fastener 20 which is secured in a loop 21 provided in the free end of the elastic member 1. The fastener 20 may be constructed of wire or sheet material and has an extension 23 formed integral therewith which is located between the layers of material forming the loop 21 in order to stiffen that portion of the loop which is engaged by the thumb and finger when the fastener 20 is being inserted in the pocket 7 for the purpose of fastening the hook 19 within the eyelet 18.

The hose supporter constructed as herein described may be quickly assembled and cheaply constructed because of the few parts and little stitching required in assembling, while the pocket 7 entirely encloses the fastening device by which the hose supporter is attached to the leg and prevents the metal portions thereof from contacting with the leg or catching in the clothing.

I claim:

1. A hose supporter comprising an elastic member adapted to extend around the leg, a flexible member attached at one end portion of said elastic member and projecting

beyond said end portion from both sides of said elastic member, clasp members carried by said flexible member and means to fasten the free end of said elastic member between the projecting sides of said flexible member.

2. A hose supporter comprising an elastic member adapted to extend around the leg, a flexible member extending transversely around said elastic member being attached thereto at one end portion thereof, said flexible member also projecting beyond said end portion from both sides of said elastic member, and being stitched to said elastic member to form a pocket at said end, clasp members carried by said flexible member and means to fasten the free end of said elastic member within said pocket.

3. A hose supporter comprising an elastic member adapted to extend around the leg, 20 a flexible member extending transversely

around said elastic member being attached thereto at one end portion thereof, said flexible member also projecting beyond said end portion from both sides of said elastic member, and being stitched to said elastic member to form a pocket at said end, clasp members carried by said flexible member, a tip located at the end of said elastic member within said pocket, an eyelet attached to said tip and a fastener attached to the free end of said elastic member and provided with a hook adapted to engage said eyelet.

In testimony whereof I have hereunto set my hand in presence of two subscribing witnesses.

ISIDOR N. POLLINGHER.
